CLEMENT BAJ, OF LYON, FRANCE, ASSIGNOR TO COMPAGNIE FRANCAISE DES APPLICATIONS DE LA CELLULOSE, OF PARIS, FRANCE.

MACHINE FOR THE MANUFACTURE OF ARTIFICIAL TISSUES.

995,652.

Specification of Letters Patent. Patented June 20, 1911.

Application filed February 24, 1911. Serial No. 610,553.

To all whom it may concern:

Be it known that I, CLEMENT BAJ, a citizen of the French Republic, residing at Lyon, in France, have invented certain new and useful Improvements in Machines for the Manufacture of Artificial Tissues, of which the following is a specification.

The improvements forming the object of the present invention are applicable to the manufacture of artificial tissues by coating an engraved cylinder with a substance such as collodion capable of filling the depressions of the design and of being hardened by its passage through a suitable liquid.

15 The said improvements consist in constructive devices and combinations of parts adapted to assure the economic operation of the cleaning and finishing devices for the engraved cylinder and to facilitate their inspection and dismounting.

An embodiment of the improvements applied to a machine of a known kind are represented in the annexed drawing in which:—

Figure 1 is a transverse section through 25 part of the machine, Fig. 2 is a sectional elevation illustrating the mechanism for coating the engraved roller, Fig. 3 is a sectional elevation illustrating the distributor for the cleaning water and Fig. 4 is a sectional elevation illustrating a suction device for removing said water.

The engraved cylinder 1 rotates in a bath 2 containing the hardening liquid, this bath is sufficiently deep to allow the residue resulting from the cleaning or other causes to collect at the bottom of the same without touching the cylinder.

The substance to be molded is contained 40 in the trough 3 bearing against the cylinder at a short distance above the level of the hardening liquid. The outer side of the trough 3 is formed by a scraper 4 shown in detail in Fig. 2 and adapted to rock on a shaft 5, said scraper being pressed against the cylinder by means of counterweighted arms 6. The two ends of the trough 3 are movable and held in position by clamps 7 in such a manner as to be set at a distance apart suitable to the length of the engraving 45 50 on the cylinder. The shaft 5 is supported at its ends by bearings 8 (Fig. 2) the height of which can be adjusted to insure the contact of the scraper along its entire length; further the shaft 5 can slide longitudinally

in the bearings 8, to which end it receives a to and fro movement for the purpose of thoroughly distributing the substance into the engraved parts of the roller. This movement is produced by a horizontal rod 10 given a reciprocating movement and passing into a groove in a cap 9 secured to the shaft 5 by a set screw, this method of connection leaving the scraper 4 perfectly guided in its bearings and free to be acted on by the counterweighted arms. The rod 10 is fixed to a lever 11 which is given an oscillatory movement by an eccentric or the like (not shown). The opposite sides of the trough 3 are adjustable both as to height and so as to be capable of exact regulation between the scraper 4 and cylinder 1. For this purpose the said sides are fixed to the clamp 7 by a bolt 37 passing through two slots and form a joint with the surface of the cylinder by a packing piece 36.

As the cylinder 1 rotates in the direction of the arrow (Fig. 1) the engraved parts thereof become filled with the substance in the trough 3 which traverses the hardening liquid in the bath 2 as far as the point 12 where the tissue is detached after which the cylinder is cleaned by water or other suitable liquid. This liquid is distributed by means of a horizontal tube 13 provided along an axial line with a row of apertures 15 leading into a jacket 16 having at its lower part a narrow slot 17 between itself and a depending member 18 which supports a flexible band 14 which bears on the cylinder. The tube 13 shown in detail in Fig. 3 partly in section and partly in elevation, is supported at each end by a double sliding suspension member 19 by which its vertical and horizontal position can be regulated exactly; it receives the liquid centrally in a regular manner by means of a flexible tube 20; this liquid flowing along the tube without filling it and passing through the apertures 15 into the jacket 16 whence it flows through the slit 17 in a thin and even stream onto the surface of the cylinder where it is held back by the flexible band 14.

The effective length of the tube 13 can be adjusted according to the width of the engraved part of the roller by means of two tightly packed pistons 21 arranged in the tube and adjusted from the outside by the rods 22. The apertures 15 can be inspected

and cleaned if necessary by removing the jacket 16 which, for this purpose, is mounted on hinges.

After having removed the substances adhering to the cylinder the washing liquid is sucked up by lips 24 and 25 of a suction device 26 and the cylinder being cleaned can then receive another coating from the trough 3.

10 The suction device shown partly in elevation and partly in section in Fig. 4 comprises a horizontal tube 26 connected by two elbows 28 with two vertical tubes 27 fixed to the machine frame and in communication 15 with a pump which maintains a constant vacuum in the whole device. The horizontal part of the tube is provided with the lips 24, 25 forming two continuous longitudinal slits which can be caused to approach very 20 close to the surface of the cylinder without touching it. It is important that this suction device when once in position should be capable of being rapidly mounted and dismounted and also of replacement exactly in 25 position. For this purpose the horizontal part 26 which is integral with the two elbows 28 is connected to the vertical tubes by liquid tight joints formed by couplings 29, said couplings being tightened by means 30 of clamps 30 pivoted at 31 to the tubes 27 and provided with pressure screws 32 bearing on projections 33 at the upper parts of the elbows. It will be seen that by simply unscrewing the screws 32 the suction device 35 can be removed. The supports 34 of the liquid distributer or washing device may be mounted in said projections 33 so that said distributer can be removed with the suction device and the whole replaced without dis- 40 arrangement of the parts.

Similarly to the liquid distributer the effective length of the suction device can be limited according to the width of the engraving, for which purpose two grooves are 45 provided between the lips 24, 25 into which small laths 35 can be slid from each side so as to limit the length of the suction aperture.

What I claim as my invention and desire 50 to secure by Letters Patent of the United States is:—

1. In a machine for the manufacture of artificial tissues, the combination of a rotary cylinder, a paste reservoir adjacent thereto, 55 a scraper in connection with said reservoir extensible in length according to the width of the tissue to be produced and means for imparting longitudinal reciprocating movement to said reservoir.

60 2. In a machine for the manufacture of artificial tissues, the combination of a rotary cylinder, a paste reservoir adjacent thereto, a scraper in connection with said reservoir to produce a film of paste on said cylinder, 55 means for imparting a longitudinal recipro-

cating movement to said reservoir, and a bath partly inclosing said cylinder and adapted to contain a liquid to harden said paste.

3. In a machine for the manufacture of 70 artificial tissues, the combination of a rotary cylinder, a paste reservoir adjacent thereto, a scraper in connection with said reservoir to produce a film of paste on said cylinder, a washing device including a perforated 75 spraying reservoir and a flexible tongue bearing on the periphery of the cylinder and means for regulating the effective length of said washing device.

4. In a machine for the manufacture of 80 artificial tissues, the combination of a rotary cylinder, a paste reservoir adjacent thereto, a scraper in connection with said reservoir to produce a film of paste on said cylinder, a washing device for spraying the cylinder 85 after removal of the film, a suction device for drying the cylinder after spraying, means for adjusting the effective length of said suction device and means for detachably mounting the device in spaced relation 90 to the cylinder.

5. In a machine for the manufacture of 95 artificial tissues, the combination of a rotary cylinder, a paste reservoir adjacent thereto, a scraper in connection with said reservoir to produce a film of paste on said cylinder, a washing device adapted to spray the cylinder with liquid after removal of the film, a suction device for drying the cylinder after spraying, means for connecting the washing 100 device to the drying device and means whereby said devices may be simultaneously mounted and dismounted in the machine.

6. In a machine for the manufacture of 105 artificial tissues, the combination of a rotary cylinder, a paste reservoir adjacent thereto, a scraper in connection with said reservoir to produce a film of paste on said cylinder, said scraper being extensible in length according to the width of tissue to be produced, means for imparting a longitudinal reciprocating movement to said reservoir, a bath partly inclosing said cylinder for containing liquid to harden the paste, a washing device adapted to spray liquid on the 110 cylinder after removal of the film therefrom, and a suction device for drying the cylinder after spraying substantially as described.

7. In a machine for the manufacture of 120 artificial tissues, the combination of a rotary cylinder, a paste reservoir adjacent thereto, a scraper in connection with said reservoir to produce a film of paste on said cylinder, said scraper being extensible in length according to the width of tissue to be produced, means for imparting a longitudinal reciprocating movement to said reservoir, a bath partly inclosing said cylinder for containing liquid to harden the paste, a wash- 125 130

ing device including a perforated spraying reservoir and a flexible tongue bearing on the periphery of the cylinder, means for regulating the effective length of said washing device, a suction device for drying said cylinder after spraying thereof and means for regulating the effective length of said drying device.

In witness whereof I have signed this specification in the presence of two witnesses.
